UNITED STATES PATENT OFFICE

FREDERICK B. WALTER, OF WABASH, INDIANA, ASSIGNOR TO B. WALTER & COMPANY, INC., OF WABASH, INDIANA, A CORPORATION OF INDIANA

EXTENSION TABLE

Application filed October 15, 1928. Serial No. 312,732.

My invention relates to improvements in tables, and particularly to extension tables. It is one of the objects of my invention to provide an extension table wherein the extension leaves thereof may be moved from one position to another with a minimum of effort.

A further object of my invention is to provide an extension table of the above type wherein the extension leaves are mounted on slides to permit the leaves to be moved into and out of position and to provide means for readily raising the leaves as they have been moved to their outer position to bring the same to the table top level and for lowering the leaves to permit the leaves to be slid under the table top for storage.

For the purpose of disclosing my invention I have illustrated one embodiment thereof in the accompanying drawings in which Fig. 1 is a bottom plan, with the legs, of a table embodying my invention; Fig. 2 is a longitudinal sectional view showing the leaves and table top lying in the same plane preparatory to being moved to interlocking position; Fig. 3 is a view similar to Fig. 2 showing the leaves and table top moved into interlocking position; Fig. 4 is a similar view showing the leaves in extended position and moved to a plane below the table top for movement to storage position; Fig. 5 is a similar view showing the leaves moved to their storage position beneath the table top; Fig. 6 is a plan partly broken away to show the table leaf slides, and Fig. 7 a transverse detailed section of the leaf slides.

In the embodiment of the invention illustrated I provide a suitable support or base comprising transversely extending bars 1 and longitudinally extending bars 2 forming a rectangular frame. This frame may be mounted on a table pedestal or may be secured to table legs or if desired, any other type of support may be provided. The table top 3 and the extension leaves 4 and 5 are vertically movable relatively to one another

and to the base or support, the leaves being mounted on suitable slides to permit the same to be moved from storage to extension position and vice versa. To this end each leaf is provided with a pair of movable slides 6, on which the leaf is mounted. These movable slides cooperate with relatively stationary slides 7. The opposite slides of each leaf are provided with suitable racks 8 and 9 geared together by means of a pinion 10 mounted on the stationary slide so that the moving slides of the two leaves will operate in unison whereby when one leaf is moved the corresponding leaf will partake of the same movement.

In order that there may be a vertical relative movement of the table top and the leaves, I provide two pairs of levers, one on each side of the table and as each pair is similar, it will only be necessary to describe one pair. Each pair comprises two levers 11 and 12, each of which is pivotally mounted on a fulcrum ear 13 in turn stationarily mounted on the base or support. The inner ends of the levers are pivotally connected as at 14 to cause the levers to move in unison and on one side of the fulcrum member 13 each lever is pivotally connected as at 15 to a downwardly extending ear 16 mounted on the under face of the table top. The opposite end of the lever 11 is pivotally connected to an upwardly extending ear 17 mounted on a transverse bar 18 extending between the stationary slides 7 and the opposite end of the lever 12 is similarly connected to an ear 19 on a stationary bar 20 likewise extending between and connected to the stationary slides 7.

The table top at its opposite ends is provided with shoulders 21 which are adapted to interlock with overhanging shoulders 22 on the leaves.

With the above construction and the parts in the position illustrated in Fig. 5, that is, with the leaves in their retracted and storage position beneath the table top, in order

to extend the leaves it is merely necessary to pull on one or the other of the leaves. This will cause the two leaves to move to the position illustrated in Fig. 4. With the parts 5 in this position, in order to bring the leaves 4 and 5 into the same plane as that of the table top, the table top is depressed by a slight pressure, thus rocking the inner ends of the levers downwardly and causing the outer 10 ends of the levers to rise, thereby raising the leaf slides as a unit until the parts assume the position illustrated in Fig. 2, after which the leaves may be moved towards the table top until the shoulders 21 and 22 interlock 15 to prevent relative vertical movement between the leaves and the table tops.

With the leaves in their extended position as illustrated in Fig. 3, in order to move the leaves back through their storage position, 20 it is of course merely necessary to move the leaves to a further extended position as illustrated in Fig. 2, after which they may be depressed by a slight pressure on either one, which pressure will rock the levers or fulcrums, lowering the leaves and at the same 25 time raising the table top until the parts assume the position illustrated in Fig. 4, after which the leaves may be slid to their storage position beneath the table top as shown in 30 Fig. 5.

It is apparent from the above that the leaves and table top have a relative right line movement and that each is movable relatively to the other. It is further apparent that 35 both the table top and the leaves are vertically movable with a right line movement respectively to the stationary base or support.

The above construction permits of an extremely simple mounting for the parts and 40 permits of the operation of the parts without binding and with a minimum effort on the part of the operator.

I claim as my invention:

1. The combination with a suitable support, two pairs of levers fulcrumed on said support, the ends of each pair being pivotally connected, a table top supported by said levers on one side of their fulcrums, stationary extension leaf slides supported by the 45 levers of each pair on the opposite side of their fulcrums, movable leaf slides supported by said stationary slides and extension leaves mounted on said movable slides.

2. As an article of manufacture, an extension table element comprising a central bracket adapted for attachment to the under side of the table leaf, two oppositely projected connected levers pivoted on said bracket, two brackets pivotally attached to 50 each lever, one adapted for attachment to a base support and the other to an extension leaf-slide-structure.

3. A table comprising a main-leaf structure, an extension-leaf structure, comprising 55 a slidable support for the extension leaf, and

a leaf supporting structure movably mounted on the main body of the table and connecting said main-leaf structure and the extension leaf structure whereby vertical movement of either will cause opposite vertical 70 movement of the other.

4. A table comprising a main-leaf structure, an extension-leaf structure comprising a 75 slidable support for the extension leaf, and a supported lever system upon which the main-leaf structure and extension-leaf structure are mounted for opposite vertical movement.

5. A table comprising a base, a vertically-movable main-leaf, a leaf-supporting mechanism vertically movable on the base, an extension-leaf laterally slidable on said leaf-supporting mechanism, connections between the main-leaf and said leaf-supporting mechanism to reversely transmit vertically applied 80 force from one leaf to the other.

6. A table-top comprising a vertically-movable main leaf, a vertically-movable slide-support an extension-leaf carried by said slide, lever-supports, and levers carried by 85 said supports and carrying the main-leaf and slide-support for simultaneous opposite vertical movement.

7. A table top comprising a vertically-movable main leaf, a vertically-movable slide-support, two slides slidably mounted on said slide-support, two extension leaves one carried by each slide, means for causing simultaneous opposite movements of said slides, lever-supports, and levers carried by 90 said supports and carrying the main-leaf and slide-support for simultaneous opposite vertical movement.

8. A table top comprising a vertically-movable main leaf, a vertically-movable slide-support arranged beneath the main-leaf, a slide slidably mounted on the slide-support, an extension leaf carried by said slide, four lever supports, and two pairs of 100 levers of the first order pivoted to said supports and pivotally connected on opposite sides of their fulcrums to the main leaf and slide-support respectively.

9. A table top comprising a vertically-movable main leaf, a vertically-movable slide-support arranged beneath the main-leaf, two slides slidably mounted on the slide-support, intermediate connections between said slides for causing simultaneous opposite movement of said slides, two extension leaves 115 carried respectively by said slides, four lever supports, and two pairs of levers of the first order pivoted to said supports and pivotally connected on opposite sides of their fulcrums to the main leaf and slide-support respectively.

10. As an article of manufacture, an extension-table fitting comprising a pair of oppositely-extended levers of the first order, fulcrum brackets carrying said levers, a bracket 130

pivots supported on the adjacent ends of said levers, and adapted to be secured to the under side of a main-leaf structure, and two brackets each pivotally attached to the outer 5 end of one lever and adapted to be secured to an extension leaf slide structure.

In witness whereof, I, FREDERICK B. WALTER, have hereunto set my hand at Wabash, Indiana, this 11th day of October, A. D. one 10 thousand nine hundred and twenty-eight.

FREDERICK B. WALTER.
